UNITED STATES PATENT OFFICE.

CHARLES N. MORRISON, OF MIDLAND, MICHIGAN, ASSIGNEE TO THE DOW CHEMICAL COMPANY, OF MIDLAND, MICHIGAN, A CORPORATION OF MICHIGAN.

FURNACE.

1,411,450.

Specification of Letters Patent. Patented Apr. 4, 1922.

Application filed September 24, 1919. Serial No. 828,032.

To all whom it may concern:

Be it known that I, CHARLES N. MORRISON, a citizen of the United States, and a resident of Midland, county of Midland, and 5 State of Michigan, have invented a new and useful Improvement in Furnaces, of which the following is a specification, the principle of the invention being herein explained and the best mode in which I have 10 contemplated applying that principle, so as to distinguish it from other inventions.

The present improvements, relating, as indicated, to furnaces, have more particular regard to the construction of a furnace designed for destructive distillation of materials such as alcohol, for example, in the generation of ethylene. It will be understood, however, that the features of construction whereby the distribution of heat 20 throughout the furnace may be regulated and controlled, as well as other advantageous elements in the present design, may be successfully utilized in furnaces intended for widely different uses. As just indicated, one object of the invention is to secure a uniform temperature throughout the heating chamber with a consequent uniformity in results as well as increased efficiency, in that the heat is utilized to the fullest 25 advantage. A further object, having reference particularly to the use of the furnace as an ethylene generator, is the convenient and accessible location of the parts, and particularly of the pipe or equivalent duct 30 through which the alcohol or other material to be treated is passed.

To the accomplishment of the foregoing and related ends, the invention, then, consists of the means hereinafter fully described 40 and particularly pointed out in the claims, the annexed drawing and the following description setting forth in detail certain mechanism embodying the invention, such disclosed means constituting, however, but 45 one of various mechanical forms in which the principle of the invention may be used.

In said annexed drawing:

Fig. 1 is a side elevational view of one construction of furnace embodying my several improvements, such furnace being characterized by having only a single duct for the material to be heated; Fig. 2 is a transverse section of the same, the plane of the section being indicated by the line 2--2, Fig. 55 1; Fig. 3 is a similar transverse section of

a modified construction of my furnace; and Fig. 4 is a vertical section of such modified construction, the plane of the section being indicated by the line 4--4, Fig. 3.

Referring first to the simpler form of construction illustrated in Figs. 1 and 2, the heating chamber 1 will be seen to be of general cylindrical form with its axis vertically disposed, and its upper and lower ends closed save for apertures through which pass the ends of a centrally located pipe or duct 2, through which the material to be heated, for example alcohol, is passed. It will be understood that suitable connections (not shown) are provided for supplying the material to one end of such pipe, and for conducting the resultant product or products away from the other end; also that such pipe, where the furnace is used as an ethylene generator, may be filled with a suitable catalytic material, which need not be described, since it forms no part of the present invention. The combustion chamber 3 will take on various forms, depending upon the kind of fuel used, the one illustrated being designed for either gaseous or liquid hydrocarbon fuel. Such combustion chamber is preferably located on a level below the bottom of the heating chamber 1, and a vertical stack 4 rises therefrom alongside said heating chamber with which it communicates through a plurality of openings 5. The size of these openings may be graduated to vary the flow of the heated gases therethrough from furnace 3 into heating chamber 1 in order to secure proper distribution of such gases in such chamber; or, if desired, dampers or valves may be located in such openings to secure the same result, with the added advantage that the control is flexible.

Adjacent said stack 4 is a second stack 6 through which the spent gases from the heating chamber are allowed to escape, said gases passing into said stack through a series 100 of openings 7 similar to openings 5 between the chamber and stack 4. In order to prevent the heated gases from escaping directly into stack 6 following their entrance into chamber 1, a radial partition 8 extends from 105 a line on the wall of the heating chamber between the two series of openings 5 and 7 to the duct 2, as clearly shown in Fig. 2. There is also provided a deflector 9 in the combustion chamber 3 for securing the full use

effect of the blast from the hydrocarbon burner, where such is employed as the heating means, while an exterior duct 10 is connected with stack 6 preferably at a point 5 midway between its ends for leading the spent gases away.

The operation of the furnace constructed as just described should be readily apparent. The heated gases rising in stack 4 pass 10 through the regulated openings 5, thence circularly around the chamber 1 to the exit openings 7 into stack 6. The duct 2 within said chamber 1 is accordingly not only heated substantially around its entire circumference, but the gases are uniformly distributed vertically through the chamber so 15 as to leave no dead spaces where the application of heat is reduced, while at the same time the excessive heating of any particular 20 part of the duct is avoided.

The modified furnace illustrated in Figs. 3 and 4 embodies features of construction very similar to those in the first described form, except that provision is made for a 25 plurality of ducts in the heating chamber, and the number of such chambers connected with a single combustion chamber is increased to two.

Such combustion chamber 11 is accordingly somewhat larger in proportion to the individual heating chamber 12, of which latter only one is shown in full in the figures, a corner of the second, appearing in Fig. 3. The feature of a baffle 13 in the combustion chamber is retained, but instead of leading directly into the vertical stack 14, and thence through the openings 15 which connect such stack with the heating chamber 12, the furnace chamber communicates with 30 a transverse passage 16 extending in front of both said chambers 12. It will be understood that by correspondingly lengthening this passage 16, any desired number of heating chambers may be connected therewith, 40 depending upon the capacity of the combustion chamber. Communication between the passage 16 and the vertical stacks 14 of the respective heating chambers 12, is secured through a suitable duct 17, as best shown in 45 Fig. 4.

Disposed alongside each vertical stack 15 is a second stack 18 which, just as in the case of stack 6 in the previously described construction, serves as the outlet for the spent 50 gases, the latter being admitted to said stack through a series of openings 19. The several stacks 18 are connected with a duct 20 through which such gases are finally carried off.

60 Instead of utilizing but a single duct for passing the material to be heated through chamber 12, a plurality of such ducts 21 is here employed, one such duct, as before, passing approximately centrally through the 65 chamber, and the others being symmetrically

grouped thereabout. As before, I again utilize the feature of a radial partition 22 extending from a line on the wall of the heating chamber between openings 15 and 19 to such centrally disposed duct 21.

70 It will be understood that, as before, the openings 15 and 19 are either graduated in size, or grouped, or else provided with dampers, so that the passage of the heated gases from stack 14 into the heating chamber 12 may be regulated and controlled. As 75 a result a uniform distribution of such gases vertically throughout the chamber can be secured, while the gases, as before, are obliged to travel circularly around the chamber by reason of the partition 22.

80 Other modes of applying the principle of my invention may be employed instead of the one explained, change being made as regards the mechanism herein disclosed, provided the means stated by any of the following claims or the equivalent of such 85 stated means be employed.

I therefore particularly point out and distinctly claim as my invention:—

90 1. In a furnace of the character described, the combination of a combustion chamber, a heating chamber, a stack, and a duct for the material to be heated passing through said heating chamber, said combustion 95 chamber being connected with said heating chamber by graduated openings whereby an approximately uniform temperature may be maintained throughout said heating chamber.

100 2. In a furnace of the character described, the combination of a combustion chamber, a heating chamber, a stack, and a duct for the material to be heated passing through said heating chamber, said heating chamber being connected with said stack by graduated 105 openings whereby an approximately uniform temperature may be maintained throughout said heating chamber.

110 3. In a furnace of the character described, the combination of a combustion chamber, a heating chamber, a stack, and a duct for the material to be heated passing through said heating chamber, said combustion 115 chamber being connected with said heating chamber by graduated openings and said heating chamber being similarly connected with said stack, whereby an approximately uniform temperature may be maintained throughout said heating chamber.

120 4. In a furnace of the character described, the combination of a combustion chamber, a vertical heating chamber of general circular cross-section, a stack, suitable openings connecting said first chamber with the second and the latter with said stack, and a duct for the material to be heated passing approximately centrally through said heating chamber.

125 5. In a furnace of the character described,

the combination of a combustion chamber, a vertical heating chamber of general circular cross-section, a stack, suitable openings connecting said first chamber with the second 15 and the latter with said stack, ducts for the material to be heated, one passing approximately centrally through said heating chamber and the others grouped thereabout, and a radial partition extending from a line on 20 the wall of said heating chamber between said openings to said central duct.

5 10 15 20

6. In a furnace of the character described, the combination of a combustion chamber, a vertical heating chamber of general cir-

cular cross-section, a stack, suitable openings connecting said first chamber with the second 15 and the latter with said stack, ducts for the material to be heated, one passing approximately centrally through said heating chamber and the others grouped thereabout, and a radial partition extending from a line on 20 the wall of said heating chamber between said openings to said central duct.

Signed by me, this 18th day of September, 1919.

CHARLES N. MORRISON.
